DROP WEIGHT CONTROL FOR LOOM PATTERN MECHANISM

Filed Sept. 26, 1925

UNITED STATES PATENT OFFICE.

KENNETH J. UNWIN, OF SHREWSBURY, AND WALTER H. WAKEFIELD, OF WORCESTER, MASSACHUSETTS, ASSIGNORS TO CROMPTON & KNOWLES LOOM WORKS, OF WORCESTER, MASSACHUSETTS, A CORPORATION OF MASSACHUSETTS.

DROP-WEIGHT CONTROL FOR LOOM PATTERN MECHANISM.

Application filed September 26, 1925. Serial No. 58,707.

This invention relates to improvements in drop weight controlling devices for the pattern mechanism of Knowles looms and an object of the invention is to provide means by which the drop weights may be moved to and held in inoperative position when it is desired to take out one of the vibrator levers forming part of the pattern mechanism.

10 The pattern mechanism of the Knowles loom comprises a series of vibrator levers each having a vibrator gear rotatably mounted thereon which is controlled as to vertical position by means of the pattern chain. A connector is attached at its inner end to the vibrator gear and at the outer end is connected to the harness jack. The harness jack is attached to the connector by an open bearing to permit separation of the parts 15 when it is desired to remove a defective vibrator lever. In order that the connectors may be properly seated at all times each is provided with a spring pressed casting known as a drop weight the function of 20 which is to hold the connector in lowered position and maintain operative contact between the same and the harness jack.

The removal of the vibrator lever requires the lifting of the drop weight with one hand 30 while the operator uses his other hand to withdraw the defective part. In order to facilitate this operation various devices have heretofore been proposed but they have usually required the disablement of all the 35 devices at once. When the loom has a number of harnesses the combined pressure of all the drop weights is considerable and it is a more particular object of our invention to provide a device for operating upon a 40 relatively small number of drop weights at a time to the end that the operation may be easier.

It is a still further object of our invention to provide means for rendering inoperative 45 the drop weights in such a manner that they may be held in raised position without continued attendance on the part of the operator.

With these and other objects in view which 50 will appear as the description proceeds our invention resides in the combination and arrangement of parts hereinafter described and set forth in the claims.

In the accompanying drawings wherein

we have shown a convenient embodiment of 55 our invention,

Fig. 1 is a vertical longitudinal section through a Knowles head looking toward the front of the loom and having our invention applied thereto,

60 Fig. 2 is a top plan view looking in the direction of arrow 2 in Fig. 1,

Fig. 3 is a detailed view of one of the cams having operative contact with the drop 65 weights,

Fig. 4 is an enlarged elevation taken in the direction of arrow 4, Fig. 1 with certain parts shown in section,

Fig. 5 is a section taken along line 5-5 70 of Fig. 4,

Fig. 6 is a view similar to Fig. 5, but showing the parts in a different position, and

Fig. 7 is a fragmentary elevation taken in the direction of arrow 7 in Fig. 5.

Referring to the drawings it will be seen 75 that we have provided a loom 10 having a head frame 11 on which are rotatably mounted upper and lower mutilated oppositely rotating cylinder gears 12 and 13, respectively. An extension of the head frame 11 is provided with a heel pin 14 which receives the outer ends of a plurality of vibrator levers 15 on each of which is rotatably mounted a vibrator gear 16. Pivoted on each vibrator gear as at 17 is 80 a connector 18 having a slotted bearing 19 to receive a gudgeon 20 formed on harness jack 21. Said jacks 21 move about a pin 22 to raise and lower the harnesses (not shown) as the vibrator gears are actuated by one 85 or the other of the cylinders.

In order to hold the connectors 18 in position so that their open bearings may be seated on the gudgeons of the jacks there is provided for each of said connectors a drop weight 23 pivoted on a rod 24 extending across the head frame. A pair of upstanding horns 25 are connected by a cross bar 26 perforated as at 27 to receive and guide a plurality of plunger rods 28, one of said rods being provided for each drop weight and having connection therewith at the lower end as at 29. Each rod is surrounded by a compression spring 30 located between the cross bar 26 and a head formed on the lower end thereof. By the mechanism described the drop weights are pushed downwardly against the connectors to hold the 90 95 100 105

open bearing 19 in operative contact with the gudgeon 20 while permitting the rising and falling of said connector due to the movement of the vibrator gears and the harness levers to which they are connected. The matter thus far described is of well-known construction and forms no essential part of our present invention.

In carrying out our improvements we provide a cross shaft 40 rotatably mounted in bearings 41 formed in the frame of the loom and having secured to the forward end thereof a normally upstanding handle 42. Secured to said shaft at spaced intervals between the sides of the frame 10 are cams 43 secured in position by means of set screws 44 and having cam faces 45 terminating in dwells 46. As shown herein the cams 43 are spaced apart a distance equal to four times the distance between the centers of adjacent vibrators, this number being chosen as it is the number of levers required for the box motion on a loom having four drop boxes on each end of the lay. Each drop weight 23 is provided with an upstanding arm 47 which lies closely adjacent the low part of the cam 43 when the handle 42 is in normal position.

The shaft 40 is provided with a plurality of circumferential grooves 48 which are spaced apart a distance equal to the space between the centers of adjacent vibrator levers. In order to hold the shaft 40 in proper angular and longitudinal position we provide a split spring 49 secured as at 50 to the loom frame and having broad and narrow fingers 51 and 52, respectively. The finger 51, which is broader than the grooves 48 to pass thereover without entering the same, is positioned for engagement with the flattened area 53 when the handle is in normal raised position to hold the handle up and the finger 52 has a rounded surface which enters the grooves 48 to position the shaft 40 longitudinally to enable the handle to be turned without endwise motion of the shaft, thus insuring contact between each drop weight and its actuating cam.

Under normal conditions the vibrator levers will be raised and lowered by the pattern mechanism 31 and the drop weights will cooperate to hold the connectors in proper position. When it is desired to remove one of the vibrator levers the shaft 40 will be moved longitudinally by means of handle 42 until one or another of the cams 43 is aligned with the upstanding arm 47 of the drop weight corresponding to the selected vibrator lever. The handle 42 is then turned in a counter-clockwise direction to the dotted line position shown in Fig. 1. This is accompanied by a backward movement of the arm 47, the dwell 46 being spaced sufficiently from the axis of the cam to raise the associated drop weight to the

dotted line position shown in Fig. 1 where it will be high enough to permit the removal of the vibrator lever.

In the particular form of head motion illustrated in the drawings sixteen harnesses have been shown and four cams so that there would be four of the notches 48 and each of the cams 43 would be movable to position to raise four of the vibrators. When the defective lever has been replaced, the handle 42 is turned back to normal position, thus restoring all the drop weights to operative position.

In order to provide for the box motion the shaft may be extended to carry one of the cams which will cooperate with the box lifting vibrators in a manner similar to that part of the mechanism similar to that devoted to the operation of the harness frames.

From the foregoing it will be seen that we have provided a convenient means for raising the drop weights and holding the same in elevated position thus freeing both hands of the operator to remove the vibrator levers. It will also be seen that only a small part of the total number of vibrators will be raised so that the strain of lifting all the drop weights is avoided.

Having thus described our invention it will be apparent that changes and modifications may be made therein by those skilled in the art and we do not wish to be limited to the details herein disclosed, but what we claim is:

1. In a loom pattern mechanism having a plurality of pattern controlled levers, harness jacks and connectors for the jacks, a drop weight for each connector, and an angularly and longitudinally movable member to raise said drop weights in relatively small groups.

2. In a loom pattern mechanism having a plurality of pattern controlled levers, harness jacks and connectors for the jacks, a drop weight for each connector, and means movable into alignment with any selected drop weight to raise and hold the same in raised position.

3. In a loom pattern mechanism having a plurality of pattern controlled levers, harness jacks and connectors for the jacks, a drop weight for each connector, and means movable longitudinally into alignment with any selected drop weight and movable angularly to raise and hold the selected drop weight in elevated position.

4. In a loom pattern mechanism having a plurality of pattern controlled levers, harness jacks and connectors for the jacks, a drop weight for each connector, means movable into alignment with any selected drop weight to raise the same, and a device to hold said means in alignment with the selected drop weight.

5. In a loom pattern mechanism having a

- plurality of pattern controlled levers, harness jacks and connectors for the jacks, a drop weight for each connector, means movable angularly and longitudinally to raise any selected drop weight, and means to hold the first named means in longitudinal alignment with the selected drop weight as the said first named means is moved angularly to raise the selected drop weight.
6. In a loom pattern mechanism having a plurality of pattern controlled levers, harness jacks and connectors for the jacks, a drop weight for each connector, means movable into alignment with any selected drop weight to raise the same, and mechanism including a yielding finger to hold said means in any one of a plurality of positions where it will be in alignment with one or another of the drop weights.
7. In a loom pattern mechanism having a plurality of pattern controlled levers, harness jacks and connectors for the jacks, a drop weight for each connector, means movable into alignment with any selected drop weight to raise the same, said means being movable angularly and longitudinally and having a series of circumferential grooves therein spaced apart a distance equal to the

distance between adjacent drop weights, and means to enter any one of the grooves depending upon the longitudinal position of said means and restrain longitudinal movement of said means.

8. In a loom pattern mechanism having a plurality of pattern controlled levers, harness jacks and connectors for the jacks, a drop weight for each connector, a longitudinally and angularly movable shaft having grooves therein spaced apart a distance equal to the distance between drop weights, devices on the shaft to engage and raise certain of the drop weights as said shaft is moved angularly, a resilient finger to enter one or another of the grooves to align the shaft and devices with respect to the drop weights, a flattened surface formed on the shaft, and a relatively broad spring to engage the flattened surface and hold the shaft in normal angular position, said spring being broader than the grooves to pass over without entering the same when the shaft is moved longitudinally.

In testimony whereof we have hereunto affixed our signatures.

KENNETH J. UNWIN.

WALTER H. WAKEFIELD.
